PAPER CLIP

John W. Hughes, Chatham, N. Y.

Application April 6, 1951, Serial No. 219,601

4 Claims. (Cl. 24—66)

1

This invention relates to paper clips and more particularly to a clip for holding a corner of a sheaf of paper sheets in folded condition to secure the sheets together.

It is among the objects of the invention to provide an improved paper clip which can be folded into a sheaf of paper sheets at one corner of the sheaf and engaged with the sheets to hold them in folded condition and superposed relationship; which engages the paper sheets in a manner such that the clip will not be accidentally displaced from the paper and the paper sheets cannot be pulled out of the clip; which is completely pre-formed and does not have to be bent into engagement with the paper; and which is simple and durable in construction, economical to manufacture of readily available sheet or strip material, is easy to apply and is neat and attractive in appearance.

Other objects and advantages will become apparent from a consideration of the following description and the appended claims in conjunction with the accompanying drawing wherein:

Figure 1 is a perspective view of a paper clip illustrative of the invention;

Figure 2 is a perspective view similar to Figure 1, but showing the opposite side of the clip from that illustrated in Figure 1; and

Figures 3 to 8 inclusive are diagrammatic views illustrating successive steps in applying the clip to a sheaf of stationery paper.

With continued reference to the drawing, the paper clip is formed from a length of strip or sheet material of a readily bendable but stiff material, such as sheet iron or a suitable metal alloy. The clip may also be formed of a material, such as a synthetic resin plastic, which may be bent to form while in a somewhat plastic or unpolymerized condition and then cured or polymerized to permanently maintain its form.

While the clip may be provided in different sizes, it has been found that a clip approximately one and one quarter inches long and one quarter of an inch wide provides satisfactory results in securing sheets of stationery paper, either letter or legal size sheets, together.

The clip, as particularly illustrated in Figures 1 and 2, comprises an intermediate portion 10 having substantially straight and parallel side edges and end portions 11 and 12 joined to the intermediate portion at the respectively opposite ends of the latter. These end portions are superposed on the same side of the intermediate portion 10 and are joined to the intermediate portion along fold lines, as indicated at 13 and 14,

which are inclined in respectively opposite directions relative to the straight, longitudinal edges of the intermediate portion at an angle of approximately 45 degrees. The end portion 12 is triangular in shape and has a length along its edge extending longitudinally of the intermediate portion substantially equal to the width of the strip. The end portion 11 has a length approximately equal to one half the length of the intermediate portion 10 and has its distal end disposed at an angle of approximately 45 degrees to its longitudinal edges.

In order to apply the clip, as generally indicated at 15 in Figures 3 to 8 inclusive, to a sheaf 16 of stationery paper and constituting a plurality of sheets of correspondence or legal paper, the clip is placed against the top sheet of the sheaf 16 near one corner, preferably the upper left-hand corner, of the sheaf, with the short end portion 12 of the clip against the outer surface of the top sheet of the sheaf of paper. The corner of the sheaf is then folded over the adjacent end of the clip to provide a first fold 17 having a width substantially equal to the width of the clip. The corner portion of the sheaf together with the clip 15 is then rolled a half turn to provide a second fold 18 which extends diagonally across the corner of the sheaf of papers with its outer edge inclined at an angle of approximately 45 degrees to the corresponding edges of the sheaf. The end of the clip on which the end member 12 is provided is now enclosed in the rolled corner of the sheaf and between the first fold 17 and the second fold 18 with the end portion 11 exposed at one end of the second fold and the end portion at the side of the clip remote from the sheaf of papers. The arrangement of the clip and the paper folds at the conclusion of the step providing the second fold 18 is particularly illustrated in Figure 4.

The corner portion of the sheaf together with the clip 15 is now rolled through a further half turn providing a third fold 19, as illustrated in Figure 5. When this third fold is completed the distal end of the end portion 11 of the clip will be adjacent one edge of the sheaf of papers, as indicated at 20 in Figure 5, and the clip is now pushed through the folds of paper in which it is received, so that the end portion 11 passes through the side of the sheaf remote from the intermediate portion 10 and the end of the clip at which the end of the intermediate portion and the end portion 11 are interconnected is brought against the adjacent edge of the sheaf of papers, as illustrated in Figure 6. Since the fold line 13

is disposed at an angle of 45 degrees to the longitudinal edges of the clip, this fold line will be parallel to the adjacent longitudinal edge of the sheaf of papers and the clip will not project materially beyond the corresponding edge of the sheaf.

The end of the clip carrying the end portion 12 is now pulled slightly away from the adjacent side of the sheaf 16 and the papers are bent near this end portion of the clip, as indicated at 21 in Figure 7, and the adjacent edge of the sheaf 16 is inserted under the end portion 12 of the clip and the papers straightened, so that the clip end portion 12 will be engaged over the adjacent edge of the sheaf substantially in opposition to the end portion 11 engaged over an edge of the sheaf at right angles to the edge engaged by the end portion 12. The clip will now be locked onto the sheaf of papers, as is particularly illustrated in Figure 8, and will not be accidentally detached from the papers, since it is enclosed in the folds made at the corner of the sheaf of papers and cannot move longitudinally relative to these folds. Also, since all of the sheets of the sheaf of papers have been folded together no single sheet can be pulled out of the clip and the papers will be positively held together and in superposed relationship to each other.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A paper clip comprising a strip of bendable material and including an intermediate portion and end portions joined to said intermediate portion at the respectively opposite ends of the latter and superposed thereon, said clip having substantially straight and parallel side edges and said end portions being joined to said intermediate portion along fold lines inclined in respectively opposite directions and at an angle of approximately 45 degrees to the straight edges of said intermediate portion and one of said end portions being materially longer than the other.
2. A paper clip comprising a member of elongated rectangular shape in transverse cross section and including an intermediate portion hav-

ing substantially straight longitudinal edges and end portions joined to said intermediate portion at the respectively opposite ends of the latter along fold lines inclined in respectively opposite directions to the longitudinal edges of said intermediate portion, one of said end portions having a length materially greater than the other end portion.

3. A paper clip comprising a member of elongated rectangular shape in transverse cross section including an intermediate portion having substantially straight longitudinal edges and end portions joined to said intermediate portion at the respectively opposite ends of the latter along fold lines inclined in respectively opposite directions to the longitudinal edges of said intermediate portion, one of said end portions having substantially straight longitudinal edges and a distal end inclined relative to its longitudinal edges and the other of said end portions being triangular in shape and having a length longitudinally of said intermediate portion substantially equal to the width of the latter.

4. A paper clip comprising a member of elongated rectangular shape in transverse cross section including an intermediate portion having substantially straight longitudinal edges and end portions joined to said intermediate portion at the respectively opposite ends of the latter along fold lines inclined in respectively opposite directions and at an angle of approximately 45 degrees to the longitudinal edges of said intermediate portion, one of said end portions having substantially straight longitudinal edges and a distal end inclined at an angle of approximately 45 degrees relative to its longitudinal edges and the other of said end portions being triangular in shape and having a length longitudinally of said intermediate portion substantially equal to the width of the latter.

JOHN W. HUGHES.
